UNITED STATES PATENT OFFICE.

ROBERT LAMBERT MURRAY, OF BUSHEY HEATH, ENGLAND, ASSIGNOR TO THE TELEPHONE MANUFACTURING COMPANY, (1920) LIMITED, OF LONDON, ENGLAND, A BRITISH LIMITED LIABILITY COMPANY.

TELEPHONE.

1,412,539.

Specification of Letters Patent. Patented Apr. 11, 1922.

Application filed September 16, 1920. Serial No. 410,612.

To all whom it may concern:

Be it known that I, ROBERT LAMBERT MURRAY, a subject of the King of England, residing in Bushey Heath, Hertfordshire, 5 England, have invented certain new and useful Improvements in Telephones, of which the following is a specification.

This invention relates to telephones and in particular to a receiver and transmitter 10 secured together as an unitary device somewhat after the manner of what are known as hand-combinations.

The term "hand-combination" is herein-after employed to denote any construction in 15 which a user's transmitter and receiver are secured together as an unitary structure, whether or no it is to be held in the user's hand.

One object, and the principal object, of 20 this invention, is to reduce the loudness of what are known as sidetones, and particularly in hand-combinations whereof the transmitter is to be held against the user's throat.

25 In back-to-back hand-combinations known heretofore it has been considered necessary to employ between the transmitter and receiver a filling material to act as a damper to prevent the phenomenon known as "howling." We have found that such a damper can be dispensed with when the microphone and receiver, whereof the resistances are in 30 a pre-determined ratio one to the other, are directly connected in parallel with one another, and the microphone and receiver can therefore be both directly secured, with obvious advantages, on a rigid metallic mounting extending between the same. It has 35 heretofore been known to connect a transmitter and receiver at a station in parallel with one another for use with a common battery; in one such known arrangement an induction coil had its primary winding connected in 40 series with the microphone and its secondary winding in series with the receiver. By dispensing with the use of an induction coil the construction is still further simplified and the cost of manufacture reduced.

According to the present invention, therefore, a telephone hand-combination has its microphone and receiver connected directly in parallel with one another, and the points of electrical junction of the said two parts

are connected directly to the transmission lines, for the purpose of reducing side-tones. 55

Preferably, the at-rest resistance of the microphone and that of the receiver at a station are approximately in the ratio of 2:1.

According to another feature of the invention, a telephone hand-combination wherein 60 the microphone and receiver are mounted back-to-back on a support common to them both and are connected electrically in parallel with one another when operated, is characterized by the support being in the form of 65 a rigid metallic mounting extending between and directly secured to the microphone and receiver.

Conveniently, a telephone hand-combination having its microphone and receiver connected as described above is arranged for common battery operation and in such a manner that the said battery always tends to strengthen the permanent magnetism of the 70 receivers.

75 The accompanying drawings illustrate a construction of diver's telephone embodying this invention,

Figure 1 being a perspective view of a transmitter and receiver arranged as a hand- 80 combination;

Figure 2 being a central vertical section through the instrument on the line 2-2 of Figure 3;

Figure 3 a front elevation with the receiver 85 diaphragm and its cap removed, and

Figure 4 a diagram of the circuits.

Dealing first with the arrangement of the circuits, they are so arranged that the receiver R and transmitter T are at one station connected in parallel with one another and through the lines L-L to the transmitter T¹ and receiver R¹ at the other station which transmitter and receiver are again in parallel with one another. 90

Dealing with the actual construction shown in Figures 1-3, a cup-shaped foundation A is provided, screw-threaded externally at A¹, to engage the receiver-cap B¹, and at A² to engage the transmitter-cap C¹. 100 The receiver diaphragm is indicated at B and the transmitter diaphragm at C, each being clamped in position by its respective cap, the diaphragm B directly to the up-standing wall A³ of the foundation and the diaphragm C by means of a loose ring C².

interposed between the cap C^1 and the bottom of the foundation A.

On the right-hand side of the bottom of the foundation, as viewed in Figure 2, is mounted the microphone D, and on the left-hand side the receiver magnets seen at E. These magnets are each in the form of a semi-circle and are held in position with their similar poles opposing one another and 10 in very close proximity to one another, each pole being provided with a slight semi-circular groove to accommodate the stem of a fixing screw E^1 . One of these fixing screws further serves, by means of a lug F^1 , to hold 15 the outer pole-piece in the form of a ring F in position, while the other holds a core, concentric with the ring F, in position, by means of a lug G. The core is not seen in the drawing being surrounded by the usual operating coil G^1 .

A curved plate spring H is provided on the inner face of the wall A^3 so as to constitute a spring key for which a chin-push H^1 is provided. One end of the spring is 25 secured by screws to the wall A^3 and the other end is free to be operated by the push H^1 and make contact at H^2 with a contact plate held between blocks H^3 of insulating material against the wall A^3 . The usual 30 three flexible leads J , J^1 , J^2 are brought in through the wall A^3 at a point opposite the push H^1 and are connected in any convenient manner to their appropriate parts of the device so as to constitute a ringing and speaking 35 circuit in the usual well-known manner. As shown in Figure 4 a one-way ringing circuit comprising a bell X is provided.

On the outside of the cap B^1 of the receiver, which cap serves totally to enclose the 40 diaphragm B, there is mounted a connector K communicating by a central perforation K^1 with the space between the inside of the cap and the diaphragm B, and by means of lateral perforated branches K^2 with flexible 45 tubes, not shown in the drawing, serving to conduct the sound to the user's ears.

A strap M is provided to enable the device to be secured to the user's neck so as to present the cap C^1 to the throat in the neighbourhood of the larynx and so that the user 50 can readily depress the push H^1 with his chain.

In connecting the apparatus up care is to be taken that the battery Z and the coils G^1 55 are so interconnected that the effect of the battery is always to tend to strengthen the permanent magnets of the receivers.

Contrary to what might be expected, it is 60 found with the apparatus constructed and connected in the manner just above described, the user is not troubled with what are ordinarily known as side-tones, in spite of the fact that the transmitter is mounted directly upon the receiver. The coil G^1 and 65 the microphone D are constructed to have

resistance values such as are ordinarily employed for telephonic communication over reasonable distances for diving operations and the like, and by means of ordinary line wires or cables. For example, the receiver 70 coil may have a value of 15 ohms and the transmitter an at-rest resistance of 25 ohms. The instrument as thus constructed does not "howl" and it is believed that contributory causes to this satisfactory result are to be 75 found in the existence of the solid bottom A^4 of the foundation between the receiver and transmitter, and, in an even more important degree, to the arrangement indicated in Figure 4. It will readily be understood 80 that variations in the transmitter resistance will not, when the parts are arranged in parallel as shown, act so directly upon the receiver as when they are connected in series 85 in the usual manner. It is well-known with the receiver and transmitter in series with one another as is usual, a telephone may be made to "howl", as it is called, by holding the receiver opposite to the transmitter and the tendency to do this has heretofore militated against success of instruments in which the receiver and transmitter were mounted in very close proximity to one another and each mechanically supporting the other.

What I claim as my invention and desire 90 to secure by Letters Patent is:—

1. In a telephone system between two stations the combination of a transmitter and a receiver at one station mounted back to back upon a support common to them both, 100 connections connecting the receiver and transmitter directly in parallel with one another, a receiver and transmitter at the other station mounted and connected in relation to one another as are those at the first said station, a speech-transmitting conductor connected at one end directly to one point of electrical junction between receiver and transmitter at one station and at the other end directly to the point of junction between transmitter and receiver at the other station, a battery and a second speech-transmitting conductor connected at one end directly to the second point of junction between transmitter and receiver at one station and through said battery to the second point of junction between transmitter and receiver at the other station, substantially as set forth.

2. In a telephone system between two stations the combination of a transmitter and a receiver at one station mounted back to back upon a support common to them both, 110 connections connecting the receiver and transmitter directly in parallel with one another whereof the at-rest resistance of the microphone is approximately double that of the receiver, a receiver and transmitter at the other station mounted and connected in 115 relation to one another as are those at the 120 other station, substantially as set forth.

3. In a telephone system between two stations the combination of a transmitter and a receiver at one station mounted back to back upon a support common to them both, 125 connections connecting the receiver and transmitter directly in parallel with one another whereof the at-rest resistance of the microphone is approximately double that of the receiver, a receiver and transmitter at the other station mounted and connected in relation to one another as are those at the 130

first said station, and whereof the at-rest resistance of the microphone is approximately double that of the receiver, a transmitting conductor connected at one end directly to one point of electrical junction between receiver and transmitter at one station and at the other end directly to the point of junction between transmitter and receiver at the other station, a battery and a second transmitting conductor connected at one end directly to the second point of junction between transmitter and receiver at one station and through said battery to the second point of junction between transmitter and receiver at the other station, substantially as set forth.

3. In a telephone system between two stations the combination of a transmitter and a receiver at one station mounted back to back upon a support common to them both, connections connecting the receiver and transmitter directly in parallel with one another, a receiver and transmitter at the other station mounted and connected in relation to one another as are those at the first said station, a transmitting conductor connected at one end directly to one point of electrical junction between receiver and transmitter at one station and at the other end directly to the point of junction between transmitter and receiver at the other station, a battery and a second transmitting conductor connected at one end directly to the second point of junction between transmitter and receiver at one station and through said battery to the second point of junction between transmitter and receiver at the other station, a calling circuit comprising a line wire and a calling device in series with one another whereof one end is connected to the aforesaid bell-push and the other end is connected to the point of junction between the transmitter and receiver at the said second station, substantially as set forth.

In testimony whereof I affix my signature.
ROBERT LAMBERT MURRAY.
